United States Patent Office.

WILLIAM A. BOYDEN AND CHARLES J. MANN, OF ALTOONA, PENNSYLVANIA.

Letters Patent No. 100,007, dated February 22, 1870.

IMPROVEMENT IN VEGETABLE-CUTTERS.

The Schedule referred to in these Letters Patent and making part of the same.

To all whom it may concern:

Be it known that we, WILLIAM A. BOYDEN and CHARLES J. MANN, in the city of Altoona, county of Blair, and State of Pennsylvania, have invented a new and Improved Vegetable-Cutter; and we do hereby declare that the following is a full, clear, and exact description thereof, which will enable others skilled in the art to make and use the same, reference being had to the accompanying drawings forming part of this specification.

This invention relates to that class of vegetable-cutters which employs a reciprocating slide to carry the knife, and consists in the specific construction of the parts and their combination as a whole.

In the drawings—

Figure 1 represents a longitudinal sectional elevation of our improved cutter;

Figure 2, an end elevation partially in section, and Figure 3, a plan view.

To enable others skilled in the art to make and use our invention, we will now proceed to describe fully its construction and operation.

A base-plate of any suitable construction is provided, which has proper standards for supporting the frame A.

B represents a slide which is moved on ways, *e*, by means of the pitman *F*, wheel *G*, and crank *K*.

C represents a double-edged knife, which is securely attached to the slide *B* by means of screws, as shown, it being preferably located on a line inclined from the transverse center line in order that it may have a drawing cut.

D D represent plates of wood, or any proper material, the outer ends of which are attached to the

slide *B* in a proper manner. Their inner ends rest upon the thumb-screws *a* *a'*, as shown in fig. 1. By means of this construction the plates may be adjusted so as to permit the knife to cut fine or coarse as may be desired.

E represents a box or hopper located over the slide *B*, as shown, which is secured to the frame *A* by means of thumb-screws *b*. By means of this construction it may be readily removed when desired.

H represents a follower provided with a handle in the usual manner.

The operation is as follows:

The vegetable or other substance to be cut is placed in the box *E*, and pressed down upon the plates *D* by means of the follower. Motion is now given the slide by means of the crank, and the knife at each movement cuts a slice from the vegetable. By adjusting the plate *D* it may be made to cut fine or coarse.

When the operation is completed the box *E* may be removed by unscrewing the screws *b*. All the parts are thus easily reached for the purpose of cleaning them.

Having thus fully described our invention,

What we claim as new, and desire to secure by Letters Patent, is—

The cutter described, consisting of the base-plate, standards, frame *A*, slide *B*, knife *C*, plates *D*, with set-screws *a*, removable box *E*, with thumb-screws *b*, pitman *F*, wheel *G*, and crank *K*, when combined as described for the purpose set forth.

WM. A. BOYDEN.
CHAS. J. MANN.
